UNITED STATES PATENT OFFICE.

ERNEST HOPKINSON, OF NEW YORK, N. Y., ASSIGNOR TO GENERAL RUBBER COMPANY, OF NEW YORK, N. Y., A CORPORATION OF NEW JERSEY.

PROCESS AND APPARATUS FOR TREATING LIQUID MATERIAL.

Application filed October 27, 1923. Serial No. 671,127.

To all whom it may concern:

Be it known that I, ERNEST HOPKINSON, a citizen of the United States, residing at New York city, county of New York, and 5 State of New York, have invented a certain new and useful Process and Apparatus for Treating Liquid Material, of which the following is a full, clear, and exact description.

10 This invention relates to a process and apparatus for treating liquid material, particularly latices containing rubber, balata, or gutta percha.

The invention contemplates broadly a 15 new and novel method and apparatus for finely dividing or atomizing liquid material in general, but particularly liquids containing solid matter in suspension, like latex or a liquid fuel. It aims to reduce the cost 20 of recovering solid matter, such as rubber, from latex, both the cost of the operation and the equipment necessary to carry it on. It also aims to provide a type of construction that is readily accessible for repair or 25 replacement. Still further, it aims to provide a construction capable of assemblage with the crudest of facilities and labor, hence meeting the need of growers, and a method and apparatus capable of increased 30 yield and operation with a comparatively low pressure.

With the illustrated embodiments of the invention in mind as applied to the treatment of rubber latex and without intention to limit its scope more than is required by the prior art, the discovery may be briefly stated to consist in the filming of latex and the dispersion of the filmed latex into a finely divided spray, the comminuted particles of which are preferably dried in a 40 gaseous medium, such as hot air. The filming of the latex is preferably effected by drawing a foraminous surface or support through a bath, the films being pneumatically shattered and divided into minute liquid particles in a condition adapting them for subsequent treatment.

Preferred embodiments of the invention are diagrammatically illustrated in the accompanying drawings in which:

Figure 1 is a vertical longitudinal section through an apparatus suitable for drying

latex, a portion of the length of the chamber being omitted for convenience in the illustration;

55 Figure 2 is a plan view of the same;

Figure 3 is a longitudinal section of a preferred form of film-forming device and co-operating nozzle;

Figure 4 is a cross-section on the line 60 4-4, Figure 3, with the adjacent parts of the feeding system appearing in elevation;

Figure 5 is a plan view of a furnace 65 suitable for heating hot air to be supplied to the latex drying apparatus, a modified form of filming and spraying apparatus being shown as applied thereto for burning liquid fuel;

Figure 6 is a front elevation of the furnace shown in Figure 5;

70 Figure 7 is an enlarged detail of a float-feed controlling mechanism suitable for liquid fuels;

75 And Figure 8 illustrates diagrammatically a safety switch desirable for burner installations.

According to the invention, the liquid material is filmed and the films shattered with a concentrated stream of air or gas so as to form a mist or spray which may be variably utilized or treated. Many forms of construction involving the underlying principles of the invention may be utilized.

80 Apparatus that may be employed for obtaining rubber in solid form from latex 85 will now be detailed and the process explained in connection therewith.

Latex may be supplied from a tank 1, Figures 1 and 4, connected by hose 2 with a pan 3, the level of the liquid within which is preferably, but not necessarily, maintained substantially constant by any suitable means. One such means is illustrated in the drawings, comprising a float 4 loosely articulated to a lever 5 which is fulcrumed intermediately at 6, its remote 90 end having fixed thereto a depending rod 7, with a cross-arm 8 adapted to be pressed down upon the pipe 2, which is preferably 95 of rubber and constrictable. The size of the passage therein may thereby be varied and the supply of the latex to the pan regulated. This type of feed control does not 100 clog, being self-cleaning, and is particularly

advantageous for controlling the supply of latex, or liquids containing solid matter in suspension. If it is desired to mingle other liquid substances with the latex, similar 5 supply tanks, connections and float controls, may be provided, but these are omitted from the drawings for the sake of clearness.

While the latex or mixture may be applied to a film-forming device variously to 10 suit the characteristics of the liquid material, the construction of the film-forming device, and the subsequent treatment or use to be made of the atomized spray, it is preferred to film latex (which ordinarily consists of around 30% rubber and 70% water, and small percentages of other matter) on a perforated drum dipping into the bath. This preferred construction, as illustrated, 15 comprises a cylindrical woven wire surface 9 of, preferably, fine mesh—say 40 to the inch, but wide variation in the size of the mesh is permissible—stretched taut between flanges 10 and 11, see Figure 3, which are integral with or secured to sleeves 12, rotating 20 on a stationary hollow tube 13, that is closed at one end, as at 14. To move the foraminous surface 9, the sleeves 12 may be equipped with a gear 15 rotated by a pinion 16 on a shaft 17 turned with a hand-crank 25 or by a motor 18. Of course, the perforated surface 9 may be otherwise variously supported and rotated. The tube 13 preferably extends only a short distance beyond the pillow-blocks 19, which may be 30 split, as at 19', so that their upper halves may be swung about the hinges 20, Figure 4, to permit quick removal of the film-forming device and substitution of another in its place.

35 The tube 13 is provided with a nozzle 21 in communication with its bore, the tip of the nozzle being located close to the inner surface of the wire, the closer the better. The nozzle discharges preferably through a 40 very narrow slit extending approximately the full width of the film-forming wire surface 9. The nozzle may be directed any way desired, vertically, horizontally, or at an inclination, but is preferably located for 45 spraying latex into a horizontal chamber so as to direct the spray at a slight downward inclination to the horizontal, substantially as shown. While a multitude of individual nozzles may be employed, it is preferred to 50 shape a single nozzle so as to direct the fluid under pressure through the wire, or other foraminous construction, such as perforated sheet metal, that may be employed, in a confined or concentrated stream, blade-like.

55 The nozzle may be united integrally with the hollow shaft or the shaft may be slotted, and the nozzle suitably secured thereabout, as desired.

60 The tube 13 may be supplied with any 65 suitable fluid under pressure, from any suit-

able source, through a connection with its open end 22, preferably made through a flexible hose 23, provided with a quick attachable band-clamp or connection 24 to facilitate operations incident to removal or 70 replacement of the entire filming and spraying unit for repair, cleaning, or other purposes, without long interruption of the process. A scraper 37 of rubber or other suitable material may be mounted to wipe the 75 sides of the flanges 10 clean, as shown in Figure 3.

The latex is continuously filmed on the screen 9, probably by capillary adhesion to the metal defining the apertures, with its 80 opposite surfaces free and unsupported in a condition ideal for their blasting or shattering by a stream of air under moderate pressure, which is projected through the screen, preferably radially or at a substantial angle 85 to the extent of the films. To obtain rubber from latex, the spray of finely divided or dispersed comminuted particles is preferably directed at a slight downward inclination 90 from the horizontal into a drying chamber, indicated generally at 25, see Figures 1 and 2. This chamber may be variously proportioned and shaped to meet the production requirements of a small or large plantation, or of a regional factory. For commercial production on a large scale, however, the chamber or room 25 may be made about twice as long as high and about as wide as high, and preferably with all or most of its 95 side walls sloped or flared outwardly and downwardly, as illustrated, so as not to allow the particles to impinge or collect thereon. In general, the cross-section of the chamber will increase towards the outlet 100 end. And, in general, the arrangement should be such as to avoid the particles of liquid, or partly dried, latex from contacting with any of the surfaces of the chamber, or each other, until they have been substantially or completely dried, or at least 105 sufficiently dried so as not to coalesce together on impingement one with another. To these ends, the chamber 25 is flared lengthwise and downward, as indicated in 110 the drawings. To dry the dispersed liquid particles of latex, an inert gas, such as CO₂, may be employed, but the preferred drying medium, preferred because of its low cost, is heated air mingled with the products of 115 combustion from a furnace, which products are conducted to the chamber through an expanding duct 26, reducing the velocity of movement. The delivery end of the expanding duct 26 is preferably equipped with 120 horizontal baffles 28 spaced closer at the top than at the bottom to insure the drying medium passing down the chamber in a more or less uniform manner and to avoid 125 the setting up of eddies, or other currents, likely to carry the particles against the

65

walls. Another aim is to keep the hot air down as much as possible and the bottom of the chamber warm.

The heated air is exhausted from the far end of the chamber through a duct or ducts 29, which are desirably in communication with some form of baffled box or passage for collecting dried particles that have not previously been deposited on the bottom of the chamber. A suitable form of such collector is illustrated in the drawings as comprising four ducts 29, each equipped with a counter-balanced, or otherwise conveniently operated, blast-gate 30, and each communicating with an upright flue 31, containing a large number of boards or trays 32, which are staggered, or overlapped, as shown, to compel the escaping air to follow a tortuous path. These boards or trays are preferably supported on slides 33 for convenient removal through a hinged door, or doors, 31', at the accessible side of the flue 31. Any one of the four ducts 29 may be closed with the blast-gate 30, the door of the flue in communication therewith opened, the trays removed, the particles cleaned therefrom and collected, and returned to place while the other three flues are in operation; the capacity of three being sufficient in such case to permit the movement and escape of the heated air at a suitable rate through the drying chamber 25. Above the flues 31, a header or outlet 32' into the atmosphere is provided.

While the dried particles which settle at the bottom of the chamber may be allowed to pile up and the operation halted at intervals to allow laborers to enter the chamber and remove the rubber, it is obviously more desirable to provide for continuous operation. To this end, it is preferred to mount platforms 35 on wheels 36, or other movable agency, and advance them step by step the length of the chamber 25. These platforms 35 are preferably made of a length sufficient to span the inside walls of the chamber at the bottom thereof, and of a width practical to manipulate. The end wall 25' of the chamber, where the platforms are introduced, is brought down so as to barely clear the same, if necessary a skirt of flexible material being provided to brush against the tops thereof. The end wall of the chamber, under which the platforms carrying the dried material pass from the chamber, is preferably equipped with a vertically movable panel 38, adapted to be raised or adjusted above the deposit of rubber when the trays are moved and to be lowered sealingly down upon the rubber after the trays have been stepped forward.

The drying medium, gas or air, may be supplied to the entering duct 26 of the chamber 25 in any suitable manner and from any suitable source. Generally, the

products of combustion will be led from the furnace and cooled down to a temperature around or below 600° F., with air from the outside atmosphere admitted through a damper controlled intake into the flue from the furnace, the necessary draft being afforded by a blower or any other suitable means. It is desirable to keep the temperature of the dried particles of latex or rubber down around 212° F., or lower. These parts are all old and well known and need no detailed illustration or description.

While any suitable form of furnace may be employed, it is preferred to utilize a burner therewith, employing the broad film-forming and spraying principle of this invention to atomize liquid fuel. An illustration of one suitable form of spray burner is disclosed in Figures 5 and 6 of the drawings. Therein, the furnace is indicated at 40, with an opening 41, towards which a stationary flat nozzle 42, with a long narrow discharge slit 42' is directed, the nozzle being in communication with a blower or a fan 43, operated by a motor 44. Between the nozzle 42 and the furnace opening 41, is rotated a disk 45 provided with a fine wire mesh 46, or minute perforations, the disk being rotatably supported on a standard 47 and operated by a worm-gear 48 from a motor 49, or other suitable means. The perforations 46 or the mesh or plate are preferably provided in an annular area of the disk of a width approximating that of the furnace opening and, upon rotation of the disk, are successively presented to the stationary nozzle. The disk, as in the previously described rotor type of construction, preferably dips in liquid fuel contained in a pan 50 having an enlarged portion 51 for accommodating a float 52. The float 52, see Figure 7, is loosely articulated to a lever 53, fulcrumed intermediately at 54 and carrying a plunger 55, for closing or opening the port 56 in a pipe 57, which is connected to a fuel tank 58, the port 57 opening into a pass 59 which is in communication with the enlargement 51 of the pan. By this means, or any other of the many devices adaptable for the purpose, the liquid fuel may be maintained in the pan 50 at a level sufficient to cover the perforated area of the disk 45, the level being preferably maintained substantially constant. The furnace may be of any suitable construction for carrying on the combustion, being preferably made of fire-brick and provided with the necessary air inlets, as usual.

As current sometimes fails by reason of a shut-down or accidents at the generating station remote from the furnace, it is desirable to provide against resumption of the operation of the blower and disk until an attendant or householder arrives to properly start or resume combustion. Any suitable mechanical means may be provided to pre-

1
vent operation of the motors after failure of the current and cessation of combustion, but it is preferred to employ an electrical switch of the no-voltage release type, one such being illustrated diagrammatically in Figure 8 of the drawings mounted in one side of the line. It comprises a manually operable switch-arm 60, fulcrumed at 61, and normally urged in a counter-clockwise direction by the spring 62, which connects the bent end 63 of the switch-arm 60 with one arm of a latch 64, which is adapted to hold the switch 60 in contacting position, and which is fulcrumed at 65 to the laminated U-shaped metallic core 66, one leg of which is surrounded by a plurality of windings constituting a coil 67. One end of the coil 67 is connected by the wire 68 to the positive side, say, of the main supply leads, and the other end of the coil is connected by the wire 69 to the contact 70. A second contact 71 is connected with the positive side of the line. The circuit through the two contacts 70 and 71 is completed when the shoe 72 pivoted on the end of the arm 60 is manually moved into contact therewith. At 73 is indicated a shunt connection for temporarily cutting out the circuit through the coil 67 at the time the switch 61 is manually closed to start the operation of the motor. The contacts 70 and 71 are mounted on yielding arms to permit the shoe 72 to make temporary engagement with the pin 74 when the switch is manually operated, but while the motor is running and the switch-arm 60 stands in the position shown in solid lines in Figure 8, the shoe 72 is not in contact with the post 74. In this type of switch, assuming the motor to be running, failure of the current does not change the position of the parts. These remain as illustrated in solid lines in Figure 8. But, should the current fail and then be resumed through the night, or when there is no one in attendance, the initial surge of a comparatively heavy current through the line, called for to start the motor, energizes the magnetic core 66 sufficiently to pull down upon the adjacent end of the latch 64 and release the switch-arm 60 to the action of the tension spring 62 which, of course, throws the switch-arm 60 from the solid line to the dotted line position and opens the circuit. During the normal operation of the motor when the switch-arm 60 is closed, as shown in full lines, the strength of the current flowing through the coil 67 is not sufficient to operate the latch 64 against the force of the spring 62.

60 It is not intended to limit the invention to this type of switch, it being detailed merely for the sake of completeness, any suitable form of mechanical or electrical contrivance being usable for the purpose of preventing operation of the spray disk and

blower when no one is present to start combustion.

The operation of the apparatus and the process have been set forth fully and completely in the detailed description above, rendering unnecessary further description. It will be seen that the invention in its broadest aspects comprehends the filming and dispersion of any liquid material whether it contains solid matter or not, the filming and spraying of the material being the same in broad principle in both cases and in both, the spray is projected into a heating chamber.

It is to be understood that various changes may be made in the process and apparatus without departing from the underlying principle of spraying or atomizing in two stages, (1) filming the liquid material, followed by (2) blasting or shattering the filmed liquid with air or other gas under pressure, preferably moderate, around eight pounds. Of course, however, the pneumatic pressure at the nozzle may be varied to suit the viscosity of the liquid film to be dispersed. The perforated carrier may be made of wire, or punched sheet metal, or of any other suitable materials, the size of the perforations or mesh being preferably small, but variable, as before stated, to suit the character of the liquid material. The liquid may be applied to the perforated carrier, whether it be in the form of a cylinder or an endless belt, by dipping preferably, but also in any other manner convenient and satisfactory for the formation of the films. The perforated carrier may just barely dip into the bath, as shown in the drawings, or it may be almost completely submerged therein if the character of the liquid material treated requires in order to prevent clogging of the perforations. These and all other mechanical variations that may be made in the apparatus and procedure are comprehended. For a full understanding of the breadth and scope of the invention, reference should be made to the appended claims.

Having thus described my invention, what I claim and desire to protect by Letters Patent is:—

1. A process of drying latex or similar materials which consists in, filming the latex with opposite free surfaces, dispersing the film into liquid particles, and substantially drying the particles while dispersed.

2. A process of drying latex or similar materials which consists in, filming the latex with opposite free surfaces, dispersing the film into liquid particles, substantially drying the particles while dispersed, and amassing the dried particles.

3. A process of drying latex or similar materials which consists in, continuously filming the latex with opposite free sur-

- faces, dispersing the film into liquid particles, and substantially drying the particles while dispersed. 65
4. A process of drying latex or similar materials which consists in, filming the latex with opposite free surfaces, pneumatically dispersing the film into liquid particles, and substantially drying the particles while dispersed. 70
- 10 5. A process of drying latex or similar materials which consists in, filming the latex with opposite free surfaces, dispersing the film into liquid particles, and subjecting the particles while dispersed to a heated gaseous drying medium. 75
- 15 6. A process of drying latex or similar materials which consists in, filming the latex with opposite free surfaces, dispersing the film into liquid particles with a concentrated stream of aeriform fluid directed on the film, and substantially drying the particles while dispersed. 80
- 20 7. A process of drying latex or similar materials which consist in, filming the latex with opposite free surfaces, dispersing the film into liquid particles with a concentrated stream of air under pressure directed through the film, and substantially drying the particles while dispersed. 85
- 25 8. A process of drying latex or similar materials which consists in, continuously filming the latex with opposite free surfaces, dispersing the film into liquid particles, substantially drying the particles while dispersed, and amassing the dried particles. 90
- 30 9. A process of drying latex or similar materials which consists in, filming the latex with opposite free surfaces, pneumatically dispersing the film into liquid particles, subjecting the particles while dispersed to a heated gaseous drying medium. 95
- 35 10. A process of drying latex or similar materials which consists in, filming the latex with opposite free surfaces, dispersing the film into liquid particles, subjecting the particles while dispersed to a heated gaseous drying medium, and amassing the dried particles. 100
- 40 11. A process of drying latex or similar materials which consists in, filming the latex with opposite free surfaces, dispersing the film into liquid particles with a concentrated stream of aeriform fluid directed on the film, and substantially drying the particles while dispersed, and amassing the dried particles. 105
- 45 12. A process of drying latex or similar materials which consists in, filming the latex with opposite free surfaces, dispersing the film into liquid particles with a concentrated stream of air under pressure directed through the film, and substantially drying the particles while dispersed, and amassing the dried particles. 110
- 50 13. A process of drying latex or similar materials which consists in, continuously filming the latex with opposite free surfaces, pneumatically dispersing the film into liquid particles, and substantially drying the particles while dispersed. 115
- 55 14. A process of drying latex or similar materials which consists in, continuously filming the latex with opposite free surfaces, dispersing the film into liquid particles, and subjecting the particles while dispersed to a heated gaseous drying medium. 120
- 60 15. A process of drying latex or similar materials which consists in, continuously filming the latex with opposite free surfaces, dispersing the film into liquid particles with a concentrated stream of aeriform fluid directed on the film, and substantially drying the particles while dispersed. 125
- 65 16. A process of drying latex or similar materials which consists in, continuously filming the latex with opposite free surfaces, dispersing the film into liquid particles with a concentrated stream of air under pressure directed through the film, and substantially drying the particles while dispersed. 130
- 70 17. A process of drying latex or similar materials which consists in, filming the latex with opposite free surfaces, pneumatically dispersing the film into liquid particles, and subjecting the particles while dispersed to a heated gaseous drying medium. 135
- 75 18. A process of drying latex or similar materials which consists in, filming the latex with opposite free surfaces, pneumatically dispersing the film into liquid particles with a concentrated stream of aeriform fluid directed on the film, and substantially drying the particles while dispersed. 140
- 80 19. A process of drying latex or similar materials which consists in, filming the latex with opposite free surfaces, pneumatically dispersing the film into liquid particles with a concentrated stream of air under pressure directed through the film, and substantially drying the particles while dispersed. 145
- 85 20. A process of drying latex or similar materials which consists in, filming the latex with opposite free surfaces, dispersing the film into liquid particles with a concentrated stream of aeriform fluid directed on the film, and substantially drying the particles while dispersed in a heated gaseous medium. 150
- 90 21. A process of drying latex or similar materials which consists in, filming the latex with opposite free surfaces, dispersing the film into liquid particles with a concentrated stream of air under pressure directed through the film, and substantially drying the particles while dispersed in a heated gaseous medium. 155
- 95 22. A process of drying latex or similar

materials which consists in, filming the latex with opposite free surfaces, spraying the film, and drying the particles of the spray.

23. A process of drying latex or similar materials which consists in, capillary drawing films of latex from a pool thereof, spraying the films, and substantially drying the particles dispersed.

24. A process of drying latex or similar materials which consists in, capillary drawing films of latex from a pool thereof, spraying the films, substantially drying the dispersed particles, and amassing the dried particles.

15 25. A process of drying latex or similar materials which consists in, continuously and capillary drawing films of latex from a pool thereof, spraying the films, and substantially drying the dispersed particles.

20 26. A process of drying latex or similar materials which consists in, maintaining a pool of latex at a substantially constant level, capillary drawing films of latex from the pool, spraying the films, and substantially drying the particles while dispersed.

25 27. A process of drying latex or similar materials which consists in, maintaining a pool of latex at a substantially constant level, capillary drawing films of latex from the pool, spraying the films, substantially drying the dispersed particles, and amassing the dried particles.

30 28. A process of drying latex or similar materials which consists in, maintaining a pool of latex at a substantially constant level, capillary drawing films of latex from the pool, spraying the films into a heated gaseous drying medium, and substantially drying the particles.

35 29. A process of drying latex or similar materials which consists in, maintaining a pool of latex at a substantially constant level, capillary drawing films of latex from the pool, spraying the films into a heated gaseous drying medium, substantially drying the particles, and amassing the dried particles.

40 30. A process of drying latex or similar materials which consists in, filming latex on a moving perforated carrier, spraying the films therefrom, and substantially drying the sprayed particles.

45 31. A process of drying latex or similar materials which consists in, filming latex on a moving perforated carrier, pneumatically spraying the films therefrom, and substantially drying the sprayed particles.

50 32. A process of drying latex or similar materials which consists in, filming latex on a moving perforated carrier, spraying the films therefrom into a gaseous drying medium, drying the sprayed particles, and collecting the particles.

55 33. A process of drying latex or similar materials which consists in, filming latex on

a moving perforated carrier, pneumatically spraying the films therefrom into a gaseous drying medium, drying the spray, and amassing the particles.

34. A process of drying latex or similar materials which consists in, filming latex on a moving perforated carrier, blowing the filmed latex therefrom and dispersing it, and drying the particles of the spray.

35. A process of drying latex or similar materials which consists in, filming latex on a moving perforated carrier, blowing the filmed latex therefrom and dispersing it, drying the particles of the spray, and finally amassing the dried particles.

36. A process of drying latex or similar materials which consists in, continuously filming the latex on a moving perforated carrier, blowing the entire width of the latex filmed on the carrier therefrom and dispersing it to form a spray of comminuted particles, and drying the particles while dispersed.

37. A process of drying latex or similar materials which consists in, continuously filming the latex on a moving perforated carrier, blowing the entire width of the latex filmed on the carrier therefrom and dispersing it to form a spray of comminuted particles, drying the particles while dispersed, and finally amassing the dried particles.

38. A process of drying latex or similar materials which consists in, filming the latex on a moving perforated carrier, blowing substantially the entire width of the filmed latex therefrom and dispersing it to form a spray of comminuted particles, and substantially drying the particles in a heated gaseous medium.

39. A process of drying latex or similar materials which consists in, continuously filming the latex on a moving perforated carrier, blowing substantially the entire width of the filmed latex therefrom and dispersing it in a slowly moving current of heated gas, drying the dispersed latex, and amassing the dried particles.

40. A process of drying latex or similar materials which consists in, filming the latex from a pool thereof at one portion of the path of a moving perforated carrier, blowing substantially the entire width of the filmed latex from the carrier at another portion in its path and into a heated gaseous drying medium, and drying and amassing the dispersed particles.

41. In an apparatus for drying latex and similar material, a drying chamber, means for dispersing latex therein, means for supplying a gaseous drying medium to the chamber, means for exhausting the gaseous medium from the chamber, said last-named means including a plurality of flues, means for governing the passage of the gase-

- ous drying medium through said flues, and a plurality of trays arranged in each of said flues, so as to compel the escaping gaseous medium to follow a tortuous path.
- 5 42. In an apparatus for drying latex and similar material, a drying chamber, means for dispersing latex therein, means for supplying a gaseous drying medium to the chamber, means for exhausting the gaseous 10 medium from the chamber, said last-named means including a plurality of flues, means for governing the passage of the gaseous
- drying medium through said flues, and a plurality of shiftable trays arranged in each of said flues so as to compel the escaping 15 gaseous medium to follow a tortuous path, each of said flues being provided with a movable wall portion to permit bodily removal of the trays from the flues.
- Signed at New York city, county of New 20 York, and State of New York, this 25th day of October, 1923.

ERNEST HOPKINSON.
